MANUFACTURING COMPANY, OF MILWAUKEE, WISCONSIN, A CORPORATION OF
DELAWARE.

STEAM-TURBINE.

1,311,615.

Specification of Letters Patent.

Patented July 29, 1919.

Application filed March 24, 1913. Serial No. 757,261.

To all whom it may concern:

Be it known that JOHANN F. M. PATITZ, a citizen of the United States, residing at Milwaukee, in the county of Milwaukee and State of Wisconsin, has invented a certain new and useful Improvement in Steam-Turbines, of which the following is a specification.

This invention relates to improvements in the construction of steam turbines and particularly to improvements in devices for retaining the speed of a turbine and mechanism driven thereby, within safe limits.

An object of the invention is to provide a steam turbine especially adapted to drive a generator furnishing current to locomotive headlights or for similar purposes, which is simple in construction and efficient in operation. Another object is to provide a simple means for retaining the speed attainable by the turbo-generator unit within safe limits, thereby preventing destruction of the apparatus due to excessive speeding up caused by a sudden release of the load on the generator. It is a further object of the invention to provide a turbo-generator set in which a predetermined constant setting of the throttle means for admitting motive fluid to the prime mover may be maintained for all loads of the variable load generator, the speed of the unit under all load conditions being automatically retained within predetermined limits. Still another object of the invention is to provide common means for both controlling the speed of the unit and for cooling the driven elements which may be subjected to undesirable heating during normal operation.

A clear conception of an embodiment of the invention may be had by referring to the drawing accompanying and forming part of this specification in which like reference characters designate the same or similar parts in the various views.

Fig. 1 is a side elevation of a turbo-generator set showing a central vertical section through the turbine and auxiliary power consuming means or fan.

Fig. 2 is an end elevation of a turbo-generator set showing the turbine inlet throttle and the turbine exhaust.

Fig. 3 is an enlarged development of a fragment of the turbine bucket wheel showing the nozzles for directing the motive fluid

therethrough and the turbine exhaust, in section.

The turbo-generator set consists essentially of a main shaft 3, having a power consuming means such as an electric generator 1, connected to an end thereof, and having a power furnishing means or prime mover, such as a steam turbine, connected to the opposite end thereof. The electric generator 1 may be of any of the well known types, the generator herein disclosed being especially adapted to furnish a limited amount of power for furnishing current to locomotive headlights and for similar purposes. The generator 1 is mounted upon a suitable base 2 and is preferably direct connected to the prime mover which drives same.

The steam turbine consists essentially of a bucket wheel 10 which is secured to an overhanging end of the shaft extension 4. The shaft extension 4 is provided with a socket 75 which fits over the end of the main shaft 3. The socket 4 is firmly secured to the main shaft 3 by any suitable means, such as a set screw, and the bucket wheel 10 may, if desired, be secured directly to the end of the main shaft 3. The bucket wheel 10 carries a series of radial buckets 11 which, as disclosed, are of the impulse type. The turbine casing 8 and end cover 12, completely inclose the bucket wheel 10 and are removably secured to each other by means of cap screws 20. The casing 8 is secured to the common base plate 2 by means of cap screws 17. The main shaft 3 and shaft extension 4 are prevented from floating or moving longitudinally by means of a suitable adjustable cap screw 13 which forms a thrust bearing and which is capable of being locked to the cover 12 in a predetermined position.

The high pressure inlet pipe 16, through which the motive fluid is admitted to the turbine, is controllable by means of a suitable throttle means disclosed as a valve 20. The discharge from the inlet pipe 16 is directed into the high pressure admission nozzle 19, which is capable of transforming the steam pressure into velocity and of directing the steam at high velocity against the vanes or buckets 11 carried by the bucket wheel 10, see Fig. 3. The return nozzle casing 15 having the return nozzle passage 18 formed therein, is secured to the turbine casing 8 and is capable of receiving the

steam discharged from the buckets 11 after its first passage through the wheel, and of redirecting the steam toward the buckets 11 at a point somewhat in advance of the admission of the high pressure steam to the wheel 10. The turbine exhaust 14 receives the steam exhausted after its second passage through the wheel and conveys same to any suitable source of low pressure, such as a 10 condenser or directly to the atmosphere.

The means for automatically causing the resistance to the rotation of the shaft 3 to vary inversely as the load on the generator 1 varies, consists of a fan 5 having a series 15 of radially extending vanes or blades 6. The fan 5 is secured directly to the shaft extension 4 and may be secured directly to the shaft 3 if desired. The fan 5, as disclosed, is formed of a pair of sheet metal plates which 20 are riveted together and have portions thereof bent outwardly to form the blades 6. The baffle plate 7 is provided with a central opening forming an air duct 9 which forms a means for conducting the supply of air to the fan 5 from a point adjacent the generator 1.

During the operation of the device, the 30 throttle valve 20 is opened to a predetermined setting, thereby admitting a substantially constant amount of motive fluid to the steam turbine for a given speed. The steam admitted to the nozzle 19 through the inlet pipe 16 is directed against the buckets 11 and upon having its energy partially abstracted during passage through the wheel 35 10, is discharged from the buckets 11 into the return nozzle passage 18. In the return nozzle passage 18 the direction of the steam is changed to again become effective in driving the bucket wheel 10 in the proper direction. Upon being discharged from the 40 return nozzle passage 18, the steam is again passed through the buckets 11, after which it is discharged from the turbine inclosing 45 casing through the exhaust 14.

The power furnished by the steam turbine and controllable by means of the throttle valve 20 is sufficient to normally drive the generator 1 and the fan 5 at a desired speed 50 with normal full load on the generator 1. If, however, the load on the generator 1 decreases, the setting of the throttle valve 20 in the meantime remaining constant, the 55 tendency of the shaft 3 will be to increase in speed. Such increase in speed is, however, rapidly checked by the fan 5, the power consumed by which being directly proportional to the cube of the speed at which it is driven. It will thus be noted that as the 60 load on the generator 1 decreases, the power consumed by the fan 5 will rapidly increase, thereby retaining the total load on the shaft

3 substantially constant and preventing excessive overspeeding of the bucket wheel 10. This automatic increasing of the power 65 consumed by the fan 5 carried by the shaft extension 4 automatically causes the resistance to the rotation of the shaft 3 to vary inversely as the load on the generator 1 varies, and by properly designing the fan blade 70 6, the maximum attainable speed of the shaft 3 can be readily maintained within the desired safe limits.

During the rotation of the fan 5, the blades 6 are constantly drawing air through 75 the air duct 9 and discharging same from the periphery of the fan 5. By arranging the air duct 9 so as to receive its supply of air from a point adjacent the generator 1, the air supply drawn through the duct is 80 drawn directly through the generator 1, thereby serving to cool the elements of the generator which may be subject to undesired heating.

It should be understood that it is not desired to be limited to the exact details of construction shown and described, for obvious modifications will occur to a person skilled in the art.

It is claimed and desired to secure by Letters Patent,—

1. In combination, an electric generator having a shaft, bearings for said shaft on opposite sides of said generator, a single bucket wheel associated with an overhanging end of said shaft and a fan associated with said overhanging shaft end and located closely adjacent said bucket wheel, said fan automatically causing the resistance to the rotation of said shaft to vary as the load on said generator varies and constituting the sole means for automatically controlling the speed of said bucket wheel.

2. In combination, an electric generator having a shaft, bearings for said shaft on opposite sides of and closely adjacent said generator, a single bucket wheel associated with an overhanging end of said shaft, means for causing motive fluid to successively impinge against the buckets of said wheel, and a rigid bladed fan associated with said overhanging shaft end and located closely adjacent said bucket wheel, said fan constituting the sole means for automatically controlling the speed of said bucket wheel.

In testimony whereof, the signature of the inventor is affixed hereto in the presence of two witnesses.

JOHANN F. M. PATITZ.
